UNITED STATES PATENT OFFICE.

AUGUSTE CHANARD, OF RUEIL, FRANCE.

FUSE FOR PROJECTILES.

1,346,177.

Specification of Letters Patent. Patented July 13, 1920.

Application filed November 2, 1918. Serial No. 260,899.

To all whom it may concern:

Be it known that I, AUGUSTE CHANARD, of 16 Avenue de Paris, Rueil, Seine et Oise, in the Republic of France, chemist, have invented Improvements in or Relating to Fuses for Projectiles, of which the following is a full, clear, and exact description.

Time fuses, that is to say fuses enabling the charge of a projectile to be ignited at a pre-determined point of the travel of the projectile as hitherto devised, comprise joints, levers and numerous parts rendering the operation thereof delicate and uncertain and liable to occasion the stoppage thereof.

On the other hand the safety devices with which these fuses have to be provided are generally hard to operate, so the action thereof is uncertain.

The present invention relates to a time fuse the construction of which is of great simplicity and the working easy and certain.

This fuse is essentially characterized by the combination

Of a movable striker that is unlocked automatically,

Of a fixed anvil carrying bar,

Of a locking device consisting of balls, normally keeping the movable striker stationary, and

Of a safety device connected with the locking device of the fuse.

By way of example the accompanying drawing shows the invention applied to a fuse for aerial projectiles.

Figure 1 shows an elevation of a time fuse according to the principle of the invention.

Fig. 2 is a corresponding plan thereof.

Fig. 3 is a sectional elevation on the line AA in Fig. 1, showing the parts of the fuse before operating.

Fig. 4 also shows a section of the fuse when the parts thereof are operating.

Figs. 5 and 6 show on a larger scale another constructional form of the fuse.

Figs. 7 and 8 and Fig. 9 show two other constructional forms of the fuse.

As may be seen from Figs. 1 to 4 of the drawing the present time fuse comprises an ogival head *a* provided with a screw thread *a*¹ enabling it to be fixed on to the projectile *b*. To the base of the said ogive is screwed a plate *c* carrying a tube *d*, at the lower part of which is arranged the anvil *e*, carrying a priming *e*¹. This anvil is jammed against a shoulder *d*¹ presented by the tube *d*, by means of another tube *f* screwed into the

said tube *d*, and provided with apertures *f*¹ for the purpose of permitting fire to be communicated from within.

This tube *f* can take for this purpose a quick match, of compressed priming powder or otherwise, a detonator or any other suitable charge.

In the tube *d* there can slide with slight friction a tubular striker *g* having a reduced extremity *g*¹ and subjected to the action of a spring *h*, the tendency of which is to cause the extremity *g*¹ of the striker to strike violently against the priming *e*¹.

The striker *g* is normally kept away from the anvil *e* by means of a locking device consisting of balls *i* each of which is fixed to the end of one of the arms of a spring *j*, made of piano wire, lodged in the ogival head *a*. The other arms of these springs are embedded in seatings *j*¹ provided for this purpose on the plate *c* (Figs. 3 and 4).

The balls *i* are engaged in cavities *k* formed in the tubular upper part of the striker and they are kept in these cavities by their contact with a central rod *l*, virtually integral with the safety device.

The latter consists of a small screw *m*, placed outside the projectile *b* and fixed on to the extremity of the rod *l*. The part of this rod located above the balls *i* is screw-threaded and engaged in a tapped plug *n* screwed to the top of the ogival head *a*. The lower part of the rod *l*, against which the balls press, is smooth, and its extremity terminates in the form of a cone *l*¹.

The fuse arranged in this way operates in the following manner:

At normal times, that is to say during the transport of the projectile, the various parts of the fuse are in the position shown in Fig. 3, the striker *g* being kept raised and its spring *h* being compressed by the engagement of the locking balls *i* in the cavities *k* and by the contact of these balls with the smooth part of the rod *l*.

The diameter and position of the balls are such that when the rod *l* is engaged between the said balls the latter project slightly out of the tubular part of the striker in such a way that if in consequence of shock the springs happened to be deformed, the balls would come to bear against the plate *c* and would prevent the device from operating accidentally.

When the projectile carrying the fuse is discharged in consequence of the displace-

ment produced by the fall of the projectile the screen *m* unscrews. On account of this fact the smooth part of the rod *l* slides between the balls *i* without the latter offering any appreciable frictional resistance on account of the compression of the spring *h*.

When the conical part *l*¹ of the rod *l* reaches the level of the balls *i*, the latter, under the action of their springs *j*, begin to leave the cavities *k* in the striker *g*, and leave these cavities completely and suddenly when the extremity of the conical part of the rod reaches their level.

15 The striker *g*, being no longer held back, and being urged by the spring *h*, descends suddenly, and, with a force depending on the power of the spring strikes against the priming *e*¹ thus bringing about the ignition 20 of the charge of the projectile.

It is to be observed that the balls are held in their places by the rod *l*, which completes the locking of the device. The unlocking which will result in the fuse operating is automatic, and this operation is always insured as the unscrewing of the safety device takes place without any effort other than that of the friction of the rod *l* in the screw-threaded plug *n*.

30 Further, with this device the safety arrangement receives no overload on account of the fact of the spring acting on the striker, which leaves it its full sensitiveness of working.

35 On the other hand it is possible to, vary at will the moment of igniting the projectile by increasing or diminishing the length of the screw-threaded part of the rod *l*.

Figs. 5 and 6 show another constructional form of the present fuse.

In this modification the balls *i* supporting the striker *g* bear, not on the extremity of springs, but on the guiding tube *d* which is prolonged right to the point of 45 the ogive *a* and is screwed into the latter.

The balls *i* are free and are engaged in the cavities *k* in the tubular part of the striker by the periphery of the tube *d*. These balls are kept in their places by the 50 action of the springs *o* fixed to the tube *d* by means of screws *o'* and engaged in recesses *p* formed in this tube.

Figs. 7 and 8 show a modification of the latter device.

55 In this modification the guiding tube *d* of the striker is prolonged right to the ogival head *g* and is screwed into the latter, as has just been said. The balls *i* are kept in their places under the action of an annular ring *q* forming a spring, of suitable cross section. This ring may be open or closed.

Fig. 9 of the drawing shows another constructional form in which the balls are double, that is to say, the locking device com-

prises two rows of superposed balls united in pairs by means of levers *r* forming a spring jointed in the middle to supports virtually integral with the plate *c*.

In this case the balls in the lower row 70 are engaged in cavities in the tubular part of the striker and these balls are maintained in position in consequence of the contact of the balls in the upper row with the smooth part of the rod *l*. When the helix 75 *m* rotates the lower balls liberate the striker when the conical part *l*¹ of the rod *l* comes opposite to the upper balls.

In the constructional forms that have just been described the striker *g* carries the 80 contact head *g*¹ and the anvil *e* the priming *e*¹, but, it will be obvious that this arrangement might be reversed *i. e.*, the priming might be carried by the striker and a contact head or block by the anvil. 85

The above arrangements have only been given by way of example, and the forms, dimensions and details of construction may be varied according to circumstances without altering the principle of the invention. 90

I claim:

1. A time fuse for projectiles comprising a tubular striker, spring means for operating the striker, cavities in the sides of the striker, ball members located in said cavities 95 and locking the striker in position in readiness for operation, a central rod located in the tubular striker and having a rotating screw and a screw thread for causing axial movement thereof, spring means located at 100 the said cavities and holding the balls in contact with the central rod, said spring means being adapted to cause the release of the striker by the ball members.

2. A time fuse for projectiles comprising 105 a tubular striker, a compression spring surrounding the striker and adapted to move same longitudinally to effect the operation, cavities in the sides of the striker, balls located in the cavities and locking the striker 110 in position in readiness for operation, a rod in screw threaded engagement with the projectile and projecting into the striker, an external screw for rotating the said rod and thus causing longitudinal movement thereof, spring means positioned in the projectile and forcing the said balls against the rod, and a cone end on the rod to control the movement of the balls as same are forced inward by the spring means to cause the release of the striker. 115

3. A time fuse for projectiles, comprising a tubular striker, spring means for operating the striker, cavities in the striker, corresponding cavities in the projectile, a central 120 rod projecting into the striker, screw means for moving the rod longitudinally, balls located in said cavities, springs secured in the projectile and pressing the said balls against the said rod and adapted to force the balls 125

out of the cavities so as to release the striker when the rod moves out of engagement with the balls.

4. A time fuse for projectiles comprising
5 a hollow striker having a closed striking end,
an operating spring inclosing said striker
and compressed between the projectile and
a shoulder on the striker, cavities in oppo-
site sides of the striker, corresponding cavi-
ties in the projectile, balls located in the
cavities, a central rod projecting into the
hollow striker, an external screw for rotat-
ing said rod, a screw thread for causing a
longitudinal movement of the rod, when ro-

tated, longitudinal side springs secured to 15
the projectile and exerting pressure upon the
said balls to force same inward against the
rod, and a cone on the rod end for guiding
the balls as they are pressed inward by the
springs.

20 The foregoing specification of my "im-
provements in or relating to fuses for pro-
jectiles" signed by me this eighteenth day
of September, 1918.

AUGUSTE CHANARD.
